UNITED STATES PATENT OFFICE.

THOMAS P. BOLGER, OF GLOUCESTER, MASSACHUSETTS.

TRAP FOR REFRIGERATOR DRAIN-PIPES.

1,107,884.

Specification of Letters Patent. Patented Aug. 18, 1914.

Application filed May 20, 1912 Serial No. 698,525.

To all whom it may concern:

Be it known that I, THOMAS P. BOLGER, a citizen of the United States, residing at Gloucester, in the county of Essex and State of Massachusetts, have invented certain new and useful Improvements in Traps for Refrigerator Drain-Pipes, of which the following is a specification.

The present invention relates to certain new and useful improvements in the construction of traps for refrigerator drain pipes.

An object of the invention is to provide novel means for mounting the drip pipe and trap whereby the trap is arranged at the upper end of the drip pipe and the said drip pipe is not dependent for support upon either the back or side walls of the refrigerator.

With this and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:

Figure 1 is a vertical sectional view through the rear portion of a refrigerator constructed in accordance with the invention. Fig. 2 is an enlarged vertical sectional view through the upper end of the drip pipe and the trap, and Fig. 3 is a horizontal sectional view on the line 3-3 of Fig. 2.

Corresponding and like parts are referred to in the following description and indicated in all the views of the drawings by the same reference characters.

Specifically describing the present embodiment of the invention, the letter A designates the body portion of the refrigerator. The walls of the refrigerator are preferably formed of spaced sheet metal plates 1 having an air space 2 between the same, each of the said sheet metal plates being lined upon the interior thereof with a layer of paper 3, a layer of linofelt 4, and then a second layer of paper 5. The air space and linofelt provide a perfect insulation which prevents heat from being conducted through the walls of the refrigerator. The walls of the refrigerator are also made air tight, thereby preventing any moisture or odors from work-

ing their way into the said walls. The inner side and back walls of both the ice chamber B and provision chamber C are continuous so that when the ice rack and shelves are removed the interior walls of the refrigerator can be easily and thoroughly cleaned.

The ice rack is formed in one piece and is removable, the rear end of the ice rack being adapted to rest upon a shoulder 6 at the back of the refrigerator, while the forward end of the ice rack is designed to rest upon a cross bar 7 at the front of the refrigerator. This ice rack comprises a drip pan 8, a corrugated ice plate 9, corrugated side walls 10, and a corrugated rear wall 11. The walls 10 and 11 only extend upwardly for a portion of the whole height of the ice chamber, and the corrugations therein run vertically so as to provide for a proper circulation of air within the ice chamber. The bottom of the pan 8 has a central opening for the circulation of air, and is inclined toward a discharge opening 12 which has a nipple 13 applied thereto. As before stated, the ice rack is made in one rigid piece which is bodily removable from the refrigerator, thereby leaving practically a single chamber within the refrigerator with continuous walls which can be easily cleaned and are perfectly water tight. If necessary or desirable, the refrigerator could be cleaned by placing it upon its back and entirely or partially filling it with water, since the interior thereof is both air and water tight.

The drip pipe 14 is arranged at the back of the refrigerator and has the lower end thereof passing loosely through the bottom of the refrigerator. This drip pipe is provided at the upper end thereof with a cup 15 having a plate 16 arranged therein. The upper extremity of the drip pipe extends through the bottom of the cup and projects into the interior thereof, and the plate 16 which is secured to the sides of the cup extends over the top of the drip pipe and has the free edge thereof extended downwardly into the cup so as to project below the upper end of the drip pipe. A trap is thus provided for preventing the free circulation of air through the drip pipe into the refrigerator, the plate 16 being inclined toward the free end thereof so as to deliver any drippings into the cup. A looped piece of spring wire or metal 17 is carried by the trap and projects upwardly from the plate 16, the said looped spring member being

adapted to be forced into the discharge nipple 13 and to frictionally engage the same so as to support the drip pipe and trap in position. The drip pipe is thus supported without the necessity of fastening it to the back or side of the refrigerator, which is a very sanitary and easily cleaned arrangement. Furthermore, the trap is arranged at the top of the drip pipe instead of at the lower end thereof, and this is a very desirable feature, since the nearer the trap is to the top of the drip pipe the less likelihood there is to be odors permeating the food chambers. This drip pipe 14 may be conveniently arranged at the rear of the shelves 18 of the food chamber, the said shelves being loosely mounted upon the shoulders 19 so as to be easily removed from position at any time.

As has been previously stated, the pan 8 and ice rack 9, and corrugated sides 10 and 11 are formed in one rigid construction so as to be bodily removable from the refrigerator when it is desired to clean the interior of the same. The rear end of the pan 8 rests upon a shoulder 6 at the back of the refrigerator, while the forward edge of the pan is formed with a lip adapted to rest upon the cross bar between the doors of the ice compartment and provision compartment.

Having thus described the invention, what I claim as new and desire to secure by Letters Patent, is:

1. In a refrigerator a drip pan formed with an outlet, a removable drip pipe adapted to be supported under the outlet of the

drip pan and in communication therewith, spring means for holding the drip pipe securely in operative position with respect to the said outlet, and a trap carried by the drip pipe.

2. In a refrigerator, a drip pan formed with an outlet, a drip pipe, a trap at the upper end of the drip pipe, and a spring member carried by the trap and adapted to engage the outlet of the drip pan to support the trap and drip pipe.

3. In a refrigerator, a drip pan formed with an outlet, a removable drip pipe, a trap at the upper end of the drip pipe, a looped spring member projecting from the trap and adapted to frictionally engage the outlet of the drip pan to support the trap and drip pipe in position.

4. In a refrigerator, a drip pan formed with an outlet nipple, a drip pipe, a cup carried by the upper end of the drip pipe and through the bottom of which the drip pipe projects, a plate arranged in the cup with the free edge thereof projecting downwardly below the upper end of the drip pipe so as to form a trap, and a looped spring member projecting from the plate and adapted to be inserted in the outlet nipple of the drip pan so as to frictionally engage the same and retain the trap and drip pipe in position.

In testimony whereof I affix my signature in presence of two witnesses.

THOMAS P. BOLGER.
